(57) **CLAIM**

The ornamental design of a front cowling of an all terrain vehicle, as shown and described.

DESCRIPTION

FIG. 1 is a perspective illustration, from the front and right side, of a first embodiment of a front cowling of the all terrain vehicle of our design;

FIG. 2 is a top view thereof;

FIG. 3 is a front view thereof;

FIG. 4 is a right side view thereof;

FIG. 5 is a rear view thereof;

FIG. 6 is a left side view thereof;

FIG. 7 is a perspective illustration, from the front and right side, of a second embodiment of a front cowling of the terrain vehicle of our design;

FIG. 8 is a top view of FIG. 7;

FIG. 9 is a front view of FIG. 7;

FIG. 10 is a right side view of FIG. 7;

FIG. 11 is a rear view of FIG. 7; and,

FIG. 12 is a left side view of FIG. 7.

The broken lines shown in FIGS. 1 and 7 are for illustrative purposes only and form no part of the claimed design.
